UNITED STATES PATENT OFFICE.

OSCAR WOODWARD, OF MONTCLAIR, NEW JERSEY, ASSIGNOR, BY MESNE ASSIGNMENTS, TO REMINGTON TYPEWRITER COMPANY, OF ILION, NEW YORK, A CORPORATION OF NEW YORK.

TYPE-WRITING MACHINE.

1,124,828.

Specification of Letters Patent.

Patented Jan. 12, 1915.

Application filed October 12, 1911. Serial No. 654,276.

To all whom it may concern:

Be it known that I, OSCAR WOODWARD, citizen of the United States, and resident of Montclair, in the county of Essex and State of New Jersey, have invented certain new and useful Improvements in Type-Writing Machines, of which the following is a specification.

My invention relates to supporting feet for writing machines and the principal object of said invention is to provide improved devices of the character specified.

To the above and other ends my invention consists in the features of construction, combinations of devices and arrangements of parts hereinafter described and particularly pointed out in the claim.

In the accompanying drawings, Figure 1 is a fragmentary side elevation; partly in section, showing part of the machine frame and one of the supporting feet attached thereto, the view showing the inner side of the forward left-hand portion of the base of the machine. Fig. 2 is a vertical sectional view, taken on a plane represented by the line $x-x$ of Fig. 1 and looking in the direction of the arrows at said line. Fig. 3 is a vertical longitudinal section of the foot proper and its associate sleeve. Fig. 4 is a detached view in elevation of the part hereinafter referred to as a tapered nut or expanding device. Fig. 5 is a perspective view of a two-part sleeve or tube, which is adapted to be arranged within the foot proper. Figs. 6, 7 and 8 are perspective views of modified forms of sleeves or tubes. Fig. 9 is a view corresponding to Fig. 2 but showing a modified construction.

Referring first to Figs. 1 to 5 of the drawings, 1 indicates the base frame of a type-writing machine, such, for example, as the No. 10 Remington typewriter. The side of the base is formed with a vertical semi-circular groove or depression 2. As shown in Fig. 2 the lower end of the groove is flared or tapered, as indicated at 3, to provide a socket portion. Secured to the side of the base as by rivets 4 is a foot bracket 5 of sheet metal or the like, said bracket bridging the groove 2 and being rounded or curved as indicated at 6, thus providing together with the lower flaring portion 3 of the groove 2 a foot receiving socket, the socket portion 6 complementing the socket

portion 3. As is clear from Fig. 2, the rounded portion 6 of the foot bracket is tapered to conform to the tapered portion 3, so that the socket as a whole is tapered, gradually decreasing in diameter from the bottom to the top. Preferably, the socket portion 6 is pressed or otherwise formed with corrugations to provide a series of grooves or depressions 7 on the inner face.

My new and improved supporting foot comprises a foot proper 8 of rubber or rubber composition or other suitable resilient and expansible material, said foot consisting of a cylindrical base portion 9 and a tapered neck or socket-engaging portion 10, said neck being adapted to fit readily into the socket 3, 6 in the machine frame. The foot proper is formed with a vertical hole or bore 11, and the lower end of the bore 11 is enlarged or counterbored at 12. The bore 11 receives a lining in the form of a metal tube or sleeve 13 which may comprise two halves or portions 14, as shown in Figs. 2, 3 and 5. The diameter of the sleeve is such that when the side edges of the sleeve engage as shown in Figs. 3 and 5, said sleeve 13 may readily be slipped into the bore. The upper edge of the sleeve is beveled or tapered, as indicated at 15. Coöoperating with the sleeve are expanding elements or devices comprising a screw 16 and a conical or tapered nut 17, said devices coöoperating to force the sleeve sections apart and expand the neck 10 within the socket 3, 6, pressing the neck into the depressions 7. The screw passes upward through the sleeve and is provided with a head 18 which is adapted to pass freely through the counterbore 12 but is of greater diameter than the sleeve, so that said head engages directly with the lower end of the sleeve. The body of the screw is of such diameter that it passes freely through the sleeve but has no side play therein, the sleeve serving to center the screw and maintain the head thereof in engagement with the lower end of said sleeve. The upper end portion of the screw 16 is reduced in diameter and threaded to coöperate with the conical nut 17, which when screwed down, seats itself in the bevel 15 at the upper end of said sleeve. The outer surface of the nut is knurled, corrugated or roughened, as shown at 17^a, Fig. 4, so that the corrugations or knurls act as projections

which will catch on the corners of the sectional sleeve or split tube 13, thus preventing the nut from rotating when the screw 16 is rotated by a screw driver.

- 5 Prior to the insertion of the foot in the machine the screw 16 and nut 17 so loosely engage the sleeve or tube 13 that the latter exerts no outward pressure or expansive force on the foot proper 8. Consequently 10 the entire foot comprising the foot proper, the tube 13 and the expanding devices 16 and 17 may be readily arranged in place, the tapered neck or socket portion 10 being easily inserted from the bottom upward in 15 the flaring socket 3, 6. Thereafter the screw 16 is rotated by a screw driver, the rotation of the screw operating to draw down the conical nut into the sleeve or tube, forcing the halves or parts of the sleeve 20 apart at their upper ends as illustrated in Fig. 2 wherein the sleeve sections are shown diverging from the bottom upward, thus causing V-shaped openings or spaces 14^a between the sleeve sections. The relative 25 movement of the sleeve parts operates in turn to expand the rubber, forcing it outward and causing it to press tightly against the inner walls of the foot socket; and also to fill the depressions 7, thus rendering more 30 difficult the accidental removal or displacement of the foot. Thus it will be noted that the head of the bolt or screw bears at one end of the sleeve and the nut at the opposite end, and when the bolt is turned, the 35 head and nut act compressively endwise on the sleeve and at the same time the upper part of the sleeve is expanded to force the rubber laterally so as to interlock with the socket. It will be observed that the screw 40 and nut, instead of co-acting directly with the rubber foot proper, co-operate instead indirectly therewith through the sleeve 13. By interposing the sleeve between the expandable foot and the expanding devices the expansive force of the latter is transmitted 45 outward or radially; whereas without the sleeve this force would in large measure be transmitted upward and downward axially of the screw and would tend to completely 50 press the rubber in an up and down direction rather than expand it outwardly. Furthermore, the sleeve operates to transmit more evenly the outward pressure or expansive force to the neck 10 than would 55 be the case if the expanding devices operated directly on the foot proper.

The foot as an entirety may be removed by turning the screw backward, which ordinarily will cause its head to move downward away from the tube or sleeve without forcing the conical nut upward. After the screw has been given a few left-hand turns it may be pushed in until its head rests against the lower end of the sleeve 6, forcing 60 the expanding nut out of the tube and 65

permitting the foot to contract so that it may be easily drawn downward out of the foot socket.

Various changes may be made without departing from the scope of my invention. For example, the expandable sleeve or tube, instead of being made in two independent halves or sections, may be of the form illustrated in Fig. 6, wherein is shown a one-piece tube 19 which is split or cut downward part way from the top at a number of points, as indicated at 20, thus providing a plurality of relatively movable tongues 21. Fig. 7 shows a one-piece tube or sleeve 22 which as indicated at 23, is split throughout its entire length; while Fig. 8 shows a sleeve 24 composed of three sections 25.

In Fig. 9 is illustrated a modified construction of receptacle or socket for the foot. In the Fig. 9 construction the bracket 5 of the Fig. 1 form is replaced by a bracket which instead of a wide, corrugated curved or bridging portion 6 has a narrower, plain, strap-like bridging portion 26. This strap portion is slightly inclined toward the tapered socket portion 3 on the frame proper, thus providing a plain tapered socket 3, 26 of less height than the corresponding socket of the first described construction. The supporting foot as a whole comprising the 90 foot proper 8, the sleeve sections 14, the screw 16 and the nut 17 may be introduced into the socket 3, 26 from the bottom upward as before, but in this case the upper end of the neck 10 will project above the top of the socket portion 26. The consequence will be that when the screw and nut are contracted by drawing down the nut to expand the neck, the portion thereof contiguous to the strap 26 will be forced or 95 pressed outward very tightly against said strap while the part of the neck above the strap will bulge over the top of the strap as indicated at 10^a. It will be apparent that the bulge will effectually lock the foot in 100 place and will prevent accidental withdrawal thereof from its socket or receptacle. Other changes in construction will readily suggest themselves to those skilled in the 105 art.

It will be understood that while I have shown and described one supporting foot the machine is provided with a plurality of these feet, four being the number ordinarily employed.

It will be seen that I provide a foot which may be readily inserted in place in the machine and as readily removed therefrom; that said foot, after it has been arranged in place, may be expanded so as practically 125 to prevent accidental removal or displacement; that removal is prevented both by the abnormal friction between the foot and its socket and also by the locking action exerted in the Fig. 1 construction by the rubber 130

which fills the depressions 7 and in the Fig. 10 construction by the bulge or overlapping portion 10^a; and that in both instances what may be termed the locking portions of the 5 foot are expanded or pressed outward radially beyond the interior wall of the socket. Such prevention has been a result long sought, the dropping out or accidental pulling or forcing out of the rubber foot being 10 heretofore one of the commonest and most annoying defects in typewriting machines. My improved foot, it will be observed, is self-contained, that is to say, within the foot proper are arranged the expanding devices 15 comprising the tube and sleeve and the screw and nut, and by loosely screwing the nut on the sleeve the foot becomes practically a single element or piece for purposes of supply.

20 What I claim as new and desire to secure by Letters Patent, is:—

In a typewriting machine, the combination of a machine frame having a socket, a rubber foot piece comprising a base portion and a neck, said foot piece being provided centrally with concentric bores or openings of different diameters, the bottom of the

base portion having the bore of larger diameter and forming a shoulder at its junction with the bore or opening of smaller diameter, a split sleeve arranged within the bore of smaller diameter, a bolt passing upwardly through said bores and so that the shank of the bolt passes through the sleeve while the head of the bolt takes a seat or bearing against the lower end of the sleeve, and a tapering nut attached to said bolt and bearing non-rotatively in the upper end of said sleeve, the whole being so arranged and operated as that when the bolt is turned the nut is caused to descend upon said bolt and expand the upper end portion of said sleeve and therethrough cause a portion of the neck of the rubber foot piece to be forced laterally into interlocking engagement with 45 said socket.

Signed at the borough of Manhattan, city of New York, in the county of New York, and State of New York, this 11th day of October, A. D. 1911.

OSCAR WOODWARD.
